[57] CLAIM

The ornamental design for a faucet handle, substantially
as shown.

DESCRIPTION

FIG. 1 is a perspective view taken from the top and rear
of a faucet handle showing my new design;

FIG. 2 is a top plan view thereof;

FIG. 3 is a front elevational view thereof, the rear being
a mirror image of the front shown;

FIG. 4 is a left side elevational view thereof; and

FIG. 5 is a right side elevational view thereof.

Fig. 1.

Fig. 2.

Fig. 3.

Fig. 4.

Fig. 5.
